UNITED STATES PATENT OFFICE.

JOHN W. GRIFFIN, OF PAWTUCKET, RHODE ISLAND, ASSIGNOR TO THE GRIFFIN AUTOMATIC FIRE ALARM COMPANY, A CORPORATION OF RHODE ISLAND.

AUTOMATIC FIRE-ALARM.

SPECIFICATION forming part of Letters Patent No. 774,385, dated November 8, 1904.

Application filed March 23, 1904. Serial No. 199,546. (No model.)

To all whom it may concern:

Be it known that I, JOHN W. GRIFFIN, a citizen of the United States, residing at Pawtucket, in the county of Providence and State 5 of Rhode Island, have invented a new and useful Improvement in Automatic Fire-Alarms, of which the following is a specification.

This invention is an improved construction of automatic fire-alarm, the object being to 10 provide a simple and efficient device by means of which a normally open electric circuit is closed and an alarm sounded whenever the temperature of the vicinity of the device exceeds a predetermined degree, thereby sounding 15 an alarm and giving notice that excessive temperature exists at the point where the mechanism is located.

Another object of the invention is to provide a device which can be attached to any suitable 20 object or to the side wall or ceiling of a room; and a still further object is to provide a device in which the parts are exceedingly simple in construction and so arranged as to protect one another, thereby increasing the durability and 25 efficiency of the device.

With these various objects in view my invention consists in the novel features of construction hereinafter fully described, and pointed out in the claims.

30 In the drawings forming a part of this specification, Figure 1 is a perspective view of an automatic fire-alarm constructed in accordance with my invention. Fig. 2 is a vertical longitudinal sectional view of the same. Fig. 3 is an inverted bottom plan.

In carrying out my invention I employ a metallic base A, which is surrounded by a depending flange A', and arranged upon this base A is a metallic cylinder B, preferably 40 supported upon legs B', screws C passing upwardly through the base into the said legs B' for the purpose of securely fastening the cylinder to the base. This cylinder B is open at one end and closed at the opposite end, said 45 closed end having an aperture B², through

which projects the threaded end D² of the rod D, said rod extending longitudinally through the cylinder B, and is provided with a flanged cap D', which snugly fits into and closes the open end of the cylinder. A coil-spring E 50 surrounds this rod D within the cylinder and bears at one end upon the cap D' and at the other end against the closed end of the cylinder, the tendency of said spring being to project the flange-cap outwardly in the direction 55 of the arrow shown in Fig. 2. This outward movement is checked by means of a nut F, screwed upon the threaded end of the rod D, and surrounding the rod D and interposed between the end of the cylinder and the said 60 nut is a fusible washer or sleeve G, made of any suitable alloy which will melt at a temperature of 125° to 130° Fahrenheit. It will be understood, however, that this sleeve or washer can be made so that it will melt at any 65 temperature desired. When the fusible sleeve or washer melts, the spring acts to project the cap D' in the direction indicated by the arrow, such movement being utilized for the purpose 70 of closing the electric circuit, which has heretofore been held open, by keeping the cap D' away from the adjustable contact-screw H, carried by the bracket I, arranged upon the base adjacent the open end of the cylinder, said bracket being secured by means of a 75 screw K, which passes upwardly through the base, said screw also serving as a connecting means for the conductor-wire L, suitable insulation M being arranged between the bracket and base and also between the base 80 and screw, as most clearly shown in Fig. 2. Two binding-posts N and O are arranged upon the opposite end of the base and to which are connected the conductor-wires N' and O', which lead to the battery and alarm 85 mechanism. The binding-post O is insulated from the base and is connected with the conductor-wire L upon the under side of the base, so that as soon as the fusible sleeve or collar melts the circuit will be closed by 90

the flange-cap D' coming in contact with the adjustable screw H, the current being transmitted through the bracket I, screw K, and the conductor-wire L to the binding-post O. 5 The rod, cylinder, and base form the other part of the circuit. By having the fusible collar or sleeve at a point remote from the contact-points all danger of the fused mass serving to insulate the parts and break the circuit 10 is avoided. Another advantage of the arrangement herein shown is that by turning an adjusting-screw in its bracket after releasing the lock-nut H' the rod D can be forced back in the cylinder, projecting the threaded end 15 through the end of the cylinder, so that the fusible collar and nut can be easily arranged thereon. After this has been accomplished the screw H is turned back, so as to open the circuit, and the lock-nut tightened for the 20 purpose of holding the screw in that adjusted position. Thus the apparatus is quickly and easily adjusted, and all of the operative parts being securely protected the device will remain in operative condition indefinitely. The 25 moment, however, the temperature of the vicinity of the device reaches a predetermined point the collar will melt, and the spring will immediately project the rod so as to bring the cap D' in contact with the screw H, thereby 30 closing the circuit and sounding the alarm. The base is flanged to afford ample room for the connecting-screws, and the base is also provided with opening A² to permit screws to be passed therethrough, so that the device can 35 be screwed either to the side wall or ceiling of a room. The spring being contained within the cylinder is thoroughly protected against dust, dirt, or any other foreign matter, and the cap D' snugly fits the open end of the cylinder and prevents the accumulation of dust 40 or dirt in said cylinder.

It will thus be seen that I provide a simple and efficient fire-alarm-operating device capable of carrying out all of the objects herein 45 mentioned.

Having thus fully described my invention, what I claim as new, and desire to secure by Letters Patent, is—

1. A device of the kind described comprising a base having a cylinder arranged thereon, said cylinder and base constituting part of the circuit, said cylinder being open at one end and closed at the other end, said closed end having an aperture produced therein, a spring-actuated rod arranged longitudinally 55 within the cylinder and having a threaded end projecting through the aperture in the end of the cylinder, said threaded end carrying a nut and a fusible collar arranged between the nut and end of cylinder, an adjustable contact-point arranged adjacent to and opposite the other end of the rod, said adjustable contact-point being supported upon and insulated from the base, and conductor-wires 60 extending from the contact-point and base as 65 set forth.

2. A device of the kind described comprising a base having two binding-posts thereon, one of which is insulated from said base, a cylinder arranged upon the base and constituting with said base a part of the circuit, said cylinder being open at one end and closed at the other end, said closed end being apertured, a rod arranged within the cylinder and having a threaded end projecting through the ap- 75 ertured end of the cylinder, a fusible collar and nut arranged upon the threaded end of the rod, a flanged cap attached to the opposite end of the rod, an insulated bracket attached to the base opposite the open end of the cylinder, the adjustable contact-point arranged directly opposite and in line with the flanged cap, means for locking said contact-point, the conductor-wires extending from 80 said contact-point and the conductor-wire ex- 85 tending from the base as set forth.

JOHN W. GRIFFIN.
